(57) **CLAIM**

The ornamental design for a video display harness, as shown and described.

DESCRIPTION

FIG. 1 is a perspective view of the video display harness according to the present invention.

FIG. 2 is a front view of the video display harness of FIG. 1.

FIG. 3 is a rear view of the video display harness of FIG. 1.

FIG. 4 is a left side view of the video display harness of FIG. 1.

FIG. 5 is a right side view of the video display harness of FIG. 1.

FIG. 6 is a top view of the video display harness of FIG. 1; and,

FIG. 7 is a bottom view of the video display harness of FIG. 1.

The belt is shown broken away to indicate indeterminate length.

The broken lines shown on the harness represent top stitching.
